(57) **CLAIM**

I claim the ornamental design for a DVD-CD player, as shown in the accompanying figures.

DESCRIPTION

FIG. 1 is a perspective view of a DVD-CD player showing my new design;

FIG. 2 is a top perspective view thereof;

FIG. 3 is a rear perspective view thereof;

FIG. 4 is a side perspective view thereof;

FIG. 5 is a front elevational view thereof;

FIG. 6 is a right side elevational view thereof;

FIG. 7 is a left side elevational view thereof;

FIG. 8 is a rear elevational view thereof;

FIG. 9 is a top plan view thereof; and,

FIG. 10 is a bottom plan view thereof.

The elements shown in broken lines are for illustrative purposes only and form no part of the claimed design.
